United States Patent Office

Des. 198,093
Patented Apr. 28, 1964

198,093

GOLF-CLUB COVER OR SIMILAR ARTICLE

Jack R. Bates, 130 Roca Way, Monterey Park, Calif.

Filed Dec. 9, 1963, Ser. No. 77,717

Term of patent 14 years

(Cl. D34—5)

I claim:

The golf-club cover or similar article, substantially as shown.
